UNITED STATES PATENT OFFICE.

CLARENCE A. CALDWELL, OF JACOBSBURG, OHIO.

GUARD FOR RAIL-FROGS.

1,083,799.

Specification of Letters Patent.

Patented Jan. 6, 1914.

Application filed June 28, 1911. Serial No. 635,764.

To all whom it may concern:

Be it known that I, CLARENCE A. CALDWELL, a citizen of the United States, residing at Jacobsburg, in the county of Belmont 5 and State of Ohio, have invented new and useful Improvements in Guards for Rail-Frogs, of which the following is a specification.

This invention relates to guards for rail frogs or like parts of a rail structure where intersecting rails form an intervening space in which the foot is liable to become caught when one is walking over the tracks, the object of the invention being to provide a 10 guard which can be readily applied to the line rail at a point in advance of the small portion of the rail frog so as to act as an obstruction to prevent accidental movement of the foot into the V-space formed by the 15 intersecting line rails.

Another object of the invention is to provide a frog guard with means whereby it will be automatically retained in its operative position relative to the frog, the guard 20 being pivotally mounted and the said means above described serving to yieldingly support the guard so as to permit of its being depressed by the rolling stock.

Figure 1 is a plan view of a rail frog 25 showing my improved guard in its applied position relative thereto. Fig. 2 is a section on line 2—2 of Fig. 1. Fig. 3 is a perspective view of the main transverse guard. Fig. 4 is a side elevation partly in section 30 of one of the rails of the frog to which the guard is attached.

For the purpose of illustrating the invention a portion of a structure A is shown in Fig. 1 of the drawing, the said structure including a frog B which may be of any suitable well known and approved construction, the point of the frog being disposed in the usual manner between the oppositely flared portion C of the wing rails D. The wing 45 rails are connected to the line rails E in the present instance by the fish plates F. In the intervening V-space G between the line and wing rails E and D respectively, is located my improved guard 1 which comprises a longitudinal member 2 located in relatively close proximity with one of the line rails E so as to be engaged by the wheels of the rolling stock and depressed thereby in a manner to be hereinafter described. 50 The guard as located is positioned in that portion of the space G in which the foot of

one passing over the track is most liable to become caught, and as illustrated, that portion of the member 2 nearest the small or point end of the frog B is apertured, at 3, 60 to receive the fish plate bolt 4. This bolt is relatively long, being provided with the usual clamping nut 5, whereby the bolt is retained in its adjusted position upon the rail and fish plate respectively. The bolt is 65 provided with spaced washers 6 which are located at the sides of the member 2 and securely positioned with respect thereto by the retaining nut 7.

At the opposite end the member 2 of the 70 guard is provided with a horizontal stop 8 and a main transverse guard 9, the latter extending in an opposite direction to the stop 8 so as to effectively span the space G. A spring 10 is operatively connected, at 11, to 75 the member 2 of the guard so as to hold the same normally in an elevated position. In the elevated position of the guard, the stop 8 engages beneath the tread of the adjacent line rail E, as shown. From the construction described, it will be readily understood 80 that the guard may be applied to various forms of rail structures where it is desired to prevent the accidental catching of the foot in the intervening space between rails 85 of the structure which are disposed in intersecting planes with relation to each other, the guard being adapted to engage the foot to positively prevent the same from working into that portion of the space in which the foot is most liable to become caught and possibly positively yield so as to prevent one 90 from dislodging his foot before the approach of a train. By providing the spring 11 the guard 1 may be depressed by the 95 train. The guard 9 is provided at one end with a threaded stud 12 which is removably fitted in a correspondingly formed socket in the member 2. By constructing the member 2 as just described, guards 9 of 100 different lengths may be interchangeably associated with the member according to the space between the line rails of the track structure. The bolt 4 serves as a pivot for the guard member 2 and holds said member in its normal position when the angular end thereof is not depressed by the weight of a 105 car thereon.

I claim:

1. A frog guard consisting of an arm having pivotal connection with one of the frog rails and disposed in spaced relation there-

to, an abutment member angularly secured to said arm and movable therewith, and a spring for holding the member in a normally elevated position.

5. 2. A frog guard consisting of an arm having pivotal connection with one of the frog rails and having an angular terminal, an abutment member secured in angular relation to said first member, a spring for holding said first member, normally elevated and

10. a stop for engaging said angular end.

3. In a guard, the combination with spaced rails, an arm pivoted in close prox-

imity to one of said rails and having an angular terminal forming a stop for said arm, 15 a guard member removably secured at a right angle to said arm and adapted to engage the other of said rails, and means for holding said arm normally elevated.

In testimony whereof I affix my signature 20 in presence of two witnesses,

CLARENCE A. CALDWELL.
